METHOD OF MAKING BUNG OPENINGS

Charles T. Draper, Cleveland Heights, Ohio, assignor to The Draper Manufacturing Company, Cleveland, Ohio, a corporation of Ohio

Application December 16, 1938, Serial No. 246,119

9 Claims. (Cl. 29—148.2)

The invention relates generally to bung openings for metallic containers, barrels, drums, vessels, packages and the like, utilized for shipping, storing, and dispensing fluid, liquid or semi-solid materials; and relates more particularly to the manufacture of a threaded container bung opening neck integrally in a single sheet metal blank by drawing, rolling and metal working operations.

Metallic containers heretofore have been provided almost universally with cast, forged or specially pressed bung rings or bushings having internal threads; the bung rings being secured in a liquid-tight manner by seaming, welding, or the like, to the container wall. Ordinarily, threads are cut in the bung rings or bushings before the same are secured to the container wall.

The manufacture of such bung rings, the threading of the same, and the securing of the bung rings to the container wall, are each relatively expensive operations, adding materially to the cost of manufacturing metallic containers. Moreover, with prior constructions, it is frequently necessary to utilize two or more gaskets in order to assure a liquid-tight closure between the bung opening and plug, and at the place of securement between the bung ring and the container wall.

I have developed an entirely new type of integral threaded bung opening for a metallic container by providing a sheet metal wall of a container with an integral tubular neck having internal and external V-sided threads formed therein, one of which is a standard pipe thread, and the metal forming the internal and external threads being internally and externally roller swaged throughout as shown in my co-pending application, Serial No. 181,875, filed December 27, 1937 (Patent No. 2,156,237); and the threading of such a neck may be carried out on apparatus such as disclosed in my co-pending application, Serial No. 181,874, filed December 27, 1937 (Patent No. 2,145,587).

It is desirable, if not necessary, that such an integral threaded neck be provided with a flange at its outer end, not only for seating a liquid-tight sealing gasket between the same and a lapping part of a closure plug, but also for providing a shoulder for securing a tamper sealing cap to the container closure construction.

It is therefore a primary object of the present invention to reduce the cost of manufacturing metallic containers by greatly reducing the cost of providing bung openings therefor.

It is a further object of the present invention to provide a method for making an integral bung opening neck in a wall of a metallic container formed from twenty-four to twelve gauge rolled steel with internal and external roller swaged thread formations, one of which is a standard pipe thread.

It is likewise an object of the present invention to provide a method of making an outwardly projecting integral bung opening neck in a sheet metal container wall terminating in an outturned flange and having inner and outer pipe thread formations in the neck between the wall and flange, one of which is a standard pipe thread.

Moreover, it is an object of the present invention to provide a method of making an outwardly projecting bung opening neck terminating in an outturned flange integrally in a sheet metal container wall having an internal standard pipe thread formation in the neck between the wall and flange.

It is also an object of the present invention to provide a method of making an outwardly projecting bung opening neck integral with a sheet metal container wall and terminating in a flange, having threads formed in the neck between the wall and flange disposed from the neck oppositely from the direction in which the flange extends.

Moreover, it is an object of the present invention to provide a method of making an outwardly projecting threaded bung opening neck integral with a sheet metal container wall in which the metal in the neck wall is swaged, deformed, cold rolled, ironed, burnished, spun, stretched, smoothed and hardened by working between roller dies to thicken the same at different regions for providing V-sided pipe threads in said neck wall, one of which is a standard pipe thread.

Moreover, it is an object of the present invention to provide a method of making a container bung opening construction having characteristics described in one or more of the preceding objects, and which is adapted to receive any one of a number of different types of closure plugs provided with standard pipe threads.

Also, it is an object of the present invention to provide a method of making a container bung opening construction having characteristics defined in one or more of the above objects, to which a tamper-seal may be readily applied.

These and other objects and advantages apparent to those skilled in the art from the following description and claims may be attained by the methods, method steps and operations of

making a bung opening hereinafter set forth in detail and claimed, preferred steps of which are shown in the accompanying drawings, and which may be stated in general terms as including, drawing a sheet metal blank to form an integral neck projecting therefrom defining an opening; forming an internal standard pipe thread in said neck preferably by working, swaging, deforming, cold rolling, burnishing, stretching, displacing, smoothing and hardening the metal in the neck between roller dies to thicken the same at different regions; and then forming an outturned flange at the outer end of said threaded neck spaced from the wall from which the neck projects, after the neck has been threaded.

In the accompanying drawings

Figure 1 is a plan view of a sheet metal blank in which an improved integral threaded bung opening neck is to be formed, the location of such a neck being indicated, for example, by 20 dot-dash lines;

Fig. 2 is an enlarged vertical section through the flat sheet metal blank shown in Fig. 1;

Fig. 3 is a vertical section similar to Fig. 2 after a cup drawing operation has been performed on the blank of Fig. 1;

Fig. 4 illustrates a combined drawing and punching operation performed on the cupped blank of Fig. 3 to provide an integral neck defining a bung opening;

Fig. 5 is a similar view illustrating the operation of roller swaging internal and external V-sided pipe threads, one of which is a standard pipe thread, in the integral neck shown in Fig. 4, between the sheet metal wall and the end of the neck;

Fig. 6 illustrates an operation of forming, rolling or turning an outwardly projecting annular flange at the end of the threaded neck shown in Fig. 5;

Fig. 7 illustrates a slightly modified form of construction in which a flanged sleeve is slipped over the threaded neck of Fig. 5 and is thereafter secured to the sheet metal wall by forming, rolling or turning an outturned flange on the neck; and

Fig. 8 illustrates the operation of forming a flange on the threaded neck of Fig. 7 to secure the flange extending ring thereto.

Similar numerals refer to similar parts throughout the various figures of the drawings.

A sheet metal blank indicated at 10 in Fig. 1, which may be the blank from which either a head or side wall of a metallic barrel is formed; and it may be desired to form a bung opening in either or both of a barrel head or side wall as by locating the same in the blank 10 in the position indicated by dot-dash lines at 11 in Fig. 1.

The blank 10 may be introduced between suitably shaped draw dies to draw a cup 12 therein (Fig. 3) at the location indicated at 11 in Fig. 1, after which the sheet metal blank 10 cupped at 12 may be further formed by a succeeding operation in suitably shaped drawing and piercing dies to draw the neck 13 (Fig. 4) and punch out a center disk (not shown) so that the neck 13 defines a bung opening in the sheet metal blank 10. The invention, however, is not limited to the specific number and character of drawing operations used to form the integral neck 13, as these may be varied in accordance with usual practice, depending upon the size and proportions of the opening, and on the properties of the sheet metal blank and on the results desired.

The neck 13 may then be threaded in apparatus

such as disclosed in my copending application Serial No. 181,874, matured in U. S. Letters Patent No. 2,145,587 as by telescoping the neck 13 (Fig. 5) over a roller die 14 provided with a threaded annular surface having a standard pipe thread form. Another similar oppositely threaded roller die 15 may then be moved radially toward roller die 14 and at the same time the axis of roller die 15 may be rotated about the neck and about the axis of roller die 14 so as to swage, deform, cold roll, iron, burnish, spin, stretch, smooth, harden and work the zone of metal indicated at 16 between the roller dies 14 and 15 to provide V-sided pipe threads 17 in the zone 16 of said neck 13 which is stiffened and strengthened by the cold working and the provision of threads.

The working operation thickens the threaded neck wall in various regions so that the thickness of the swaged metal in the thread apices is greater in a diametrical direction than the thickness of the swaged metal in the side wall of a thread common to both the internal and external thread surfaces.

The movement of the roller die 15 radially toward the roller die 14 places the metal in the neck 13 being worked under considerable pressure; and sufficient pressure is applied and maintained and the cold rolling and ironing operation is carried out for a sufficient number of revolutions that accurate V-shape pipe threads are formed. As a result the thread formations present very smooth, cold rolled surfaces which will not seize, even if the threaded neck is formed in a steel sheet and another threaded steel member is engaged with the threaded neck.

Moreover, as shown in Fig. 5, the internal threaded surface has a standard pipe thread formation and the internal threads project inwardly of the location of the zone 16 of the neck wall prior to being threaded.

Thus, the improved method provides for forming standard pipe threads in the thin sheet metal neck wall 13 integral with the blank wall 10 without cutting the metal; which product is disclosed in my copending application Serial No. 181,875.

After the threads 17 have been rolled in the zone 16 of the neck 13, the sheet metal blank 10 may be further worked to form, turn or roll an outturned flange 18 (Fig. 6) at the outer end of the threaded neck 13 as by engaging a roller 19 against neck 13 and moving a cooperating roller 20 radially toward roller 19.

The flange 18 thus forms an abutment against 55 which a liquid sealing gasket may be clamped by a closure plug threaded into the threaded bung opening neck; and the flange 18 may also be engaged by a tamper-sealing cap for sealing the closure construction, all as illustrated in said copending product application Serial No. 181,875.

In some cases it may be desirable to extend a flange outward considerably further than shown in Fig. 6 and it may likewise be desirable to provide a shoulder on the top surface of the flange. 65 This may be accomplished as shown in Figs. 7 and 8 by telescoping a flanged ring 21 around the threaded neck 13 (Fig. 7) and then rolling, forming or turning flange 18, as shown in Fig. 8, so as to clamp the flanged ring 21 between flange 18 and wall 10. Thus, the flange at the outer end of the threaded neck is in effect, extended outward farther by flange 22 of flanged ring 21; and flange 18 and flange 22 cooperate to form a shoulder 23, which is an exceedingly advantageous

form of abutment against which a liquid sealing gasket may be clamped.

Thus, the improved method provides not only for forming a threaded bung opening neck integrally in a sheet metal wall but also provides for locating such an integral threaded neck eccentrically in a sheet metal wall as indicated at 11 in Fig. 1.

Moreover, the improved method provides for the formation of internal and external roller swaged thread formations, one of which is a standard pipe thread, in a neck integral with a sheet metal wall.

In addition, the improved method provides for the manufacture of a threaded bung opening neck terminating in an outturned flange integrally in a sheet metal wall.

Thus the present improvements appreciably reduce the cost of providing bung openings for metallic containers and therefore appreciably reduce the cost of manufacturing such metallic containers; and the present improvements overcome the difficulties and eliminate many of the expensive and complicated operations involved in the prior practice of making and securing bung rings to metallic containers.

In the foregoing description, certain terms have been utilized for brevity, clearness and understanding; but no unnecessary limitations are to be implied therefrom beyond the requirements of the prior art; because such words are utilized for descriptive purposes herein and not for the purpose of limitation, and are intended to be broadly construed.

Moreover, the invention is not limited to the production of the exact structures shown herein because the size of the opening may be varied, the length of the neck may be varied, and the size and shape of the flange at the end of the neck may be varied, to provide other structural embodiments without departing from the scope of the present method invention for manufacturing the various structures.

The words "sheet metal" used herein and in the claims are intended to include sheet, strip or plate metal of the desired or necessary gauge including steel, galvanized steel, or other metals from which it may be desired to construct metallic containers; the words "standard pipe threads" are intended to refer to the various standard pipe threads which are standard in various countries of the world, all of which threads have V-sides; and the words "threaded bung opening neck" are intended to include threaded necks integral with a sheet metal wall regardless of the size of the same and regardless of whether or not the sheet metal wall forms a wall of a sheet metal barrel, because a sheet metal wall provided with an integral threaded neck forming an opening in the wall may be used in many places other than in a sheet metal barrel or drum.

Having now described the features of the invention, the preferred steps and preferred sequence of steps used in carrying out the improved method, and the advantages and results obtained by the use of the same; the new and useful methods, method steps and operations, and reasonable mechanical equivalents thereof obvious to those skilled in the art, are set forth in the appended claims.

I claim:

1. The method of making an integral threaded flanged bung opening neck in a sheet metal wall including the steps of drawing an annular neck

in a sheet metal wall to define an opening therein, externally and internally roller swaging a zone of said neck to form external and internal smooth V-threads therein, and then forming an outturned flange on said neck spaced from said wall.

2. The method of making an integral threaded flanged bung opening neck in a sheet metal wall including the steps of drawing an annular neck in a sheet metal wall to define an opening therein; displacing a zone of the metal in said neck by externally and internally swaging the same between roller dies to form external and internal V-sided pipe threads therein, one of which is a standard pipe thread; and then forming an outturned flange on said neck spaced from said wall.

3. The method of making a threaded flanged bung opening neck in a sheet metal wall including the steps in the order named of drawing an integral annular neck in a sheet metal wall to define an opening therein, forming threads in said neck, placing a flanged ring on said neck, and then forming an outturned flange on said neck and simultaneously securing said flanged ring thereto.

4. The method of making a threaded flanged bung opening neck in a sheet metal wall including the steps in the order named of drawing an integral annular neck in a sheet metal wall to define an opening therein, forming threads in said neck, placing a ring having a flange at the outer end thereof about said neck, and then turning a flange at the outer end of said neck and simultaneously abutting and clamping the same against the ring flange.

5. The method of making an integral threaded bung opening neck in a sheet metal wall including the steps of drawing an annular neck in a sheet metal wall to define an opening therein; deforming a zone of the metal in said neck to thicken the same in different regions by externally and internally swaging and working the same between roller dies to form external and internal V-sided pipe threads therein, one of which is a standard pipe thread; and then forming an outturned flange on said neck spaced from said wall.

6. The method of making an integral threaded bung opening neck in a sheet metal wall including the steps of drawing an annular neck in a sheet metal wall to define an opening therein; displacing a zone of the metal inwardly of said neck by externally and internally swaging and working the metal between roller dies to form external and internal V-sided pipe threads in said neck, the internal threads being standard pipe threads projecting inwardly of said neck; and then forming an outturned flange on said neck spaced from said wall.

7. The method of making an integral threaded flanged bung opening neck in a sheet metal wall including the steps of drawing an annular neck eccentrically in a sheet metal blank to define an opening therein, externally and internally roller swaging a zone of said neck to form external and internal smooth V-threads therein, and then forming an outturned flange on the outer end of said neck.

8. The method of making an integral threaded bung opening neck in a sheet metal wall including the steps of drawing an annular neck eccentrically in a sheet metal wall to define an opening therein, and then externally and internally roller swaging a zone of said neck to form

external and standard internal pipe threads therein.

9. The method of making an integral threaded bung opening neck in a sheet metal wall including the steps of drawing an annular neck in a sheet metal wall to define an opening therein, and then displacing a zone of the metal in said

neck and changing the thickness of the metal therin by externally and internally swaging the same between roller dies to form external and internal V-sided pipe threads therein, one of which is a standard pipe thread.

CHARLES T. DRAPER.
